UNITED STATES PATENT OFFICE.

LESTER E. DILLON, OF CIVIL BEND TOWNSHIP, UNION COUNTY, SOUTH DAKOTA.

HAIRPIN.

Application filed July 19, 1920. Serial No. 397,463.

To all whom it may concern:

Be it known that I, LESTER E. DILLON, a citizen of the United States, and a resident of Civil Bend Township, in the county of Union and State of South Dakota, have invented certain new and useful Improvements in Hairpins, of which the following is a specification.

My invention aims to provide an improved wire hair-pin, so constructed that it may be readily inserted or withdrawn, yet is secured against displacement when in the hair. The invention will be clearly understood from the following description, reference being had to the accompanying drawing, which forms a part of this application and which is an elevation of a hair-pin constructed in accordance with the invention.

Referring to the illustration, the device consists of a U-shaped wire, preferably so formed that the portions, A, of its arms adjacent the web are in parallelism. The end portions of the arms are inclined toward each other and in the direction of the extremities of the arms, as at B. The arms are then curved outwardly from each other, then toward each other, as at C, the extreme end portions of the arms being bent to di-

verge, as at D. The parts, D, serve as diverging guide-fingers whereby, when inserting the pin in the hair, a maximum quantity of hair is admitted into the pin between the parts A and C. The bends, it will be observed, form contracted necks, which retain the hair in the pin and prevent its accidental displacement therefrom.

Having thus described my invention, what I claim as new and desire to secure by Letters Patent of the United States, is:

A hair-pin comprising a U-shaped wire, the major portions of its arms from the web being parallel, their free end portions being formed with inwardly and downwardly-inclined bends, the portions below said bends being curved outwardly in a crescent shape, the extreme end portions of the arms being straight and inclined outwardly and downwardly from said crescent-shaped portion of each arm being in a common vertical plane in parallelism with the said major portions, and said arms being spaced from each other throughout their entire length.

In testimony whereof, I have hereunto set my hand this 15th day of July, 1920.

LESTER E. DILLON.
